UNITED STATES PATENT OFFICE.

CHARLES A. RIVERS AND FRANCIS BACON STUART, OF EL PASO, TEXAS; ARA M. RIVERS ADMINISTRATRIX OF THE ESTATE OF SAID CHARLES A. RIVERS, DECEASED.

AUXILIARY-AIR-SUPPLY DEVICE FOR INTERNAL-COMBUSTION ENGINES.

Application filed August 12, 1920. Serial No. 402,996.

To all whom it may concern:

Be it known that we, CHARLES A. RIVERS and FRANCIS B. STUART, citizens of the United States, and residents of the city of 5 El Paso, in the county of El Paso and State of Texas, have invented certain new and useful Improvements in Auxiliary-Air-Supply Devices for Internal-Combustion Engines, of which the following is a description.

This invention relates to an improved auxiliary air supply device for internal combustion engines, and broadly considered 15 contemplates the provision of simple and reliable means for automatically regulating the supply of auxiliary air to the combustible mixture in accordance with the operating speed of the engine.

More particularly the present improvement 20 comprehends the provision of means for sensitively controlling the operation and adjustment of the auxiliary air supply valve by means of the rearwardly directed air current from the radiator fan with 25 which the motor is equipped.

We also propose to provide a device of the character referred to which may be readily adjusted and positioned so as to insure the requisite degree of valve opening at the 30 various engine speeds, whereby exactly the necessary volume of auxiliary air will be supplied to the mixture so as to thereby obviate the admission of an overrich mixture to the engine cylinders, which results in a 35 more or less heavy deposition of carbon, and very materially decreases the effective power developed in the operation of the engine.

Further we contemplate the provision of a very simple and reliably operating attachment or accessory for motor vehicle engines 40 which can be readily applied to various types of engines now used upon motor vehicles without requiring any radical alterations in their structure, or necessitating a 45 high degree of mechanical skill in the application of the device.

With the above and other objects in view, the invention consists in the improved construction, combination and arrangement of 50 the several parts as will be hereinafter more fully described, illustrated in the accompanying drawings, and subsequently incorporated in the subjoined claims.

In the drawings, wherein we have illustrated one satisfactory and practical embodiment of the invention, and in which similar reference characters designate corresponding parts throughout the several views:

Figure 1 is a fragmentary side elevation 55 of a motor vehicle engine having the well known Ford type of intake manifold, and showing one embodiment of our present invention in its applied position.

Figure 2 is an elevation on an enlarged 60 scale, of the attachment removed from the engine.

Figure 3 is a plan view of the device.

Figure 4 is a sectional view taken on the line 4—4 of Figure 2, and,

Figure 5 is a section taken on the line 70 5—5 of Figure 2.

Considering the drawings in detail, we have conventionally illustrated a motor vehicle engine generally indicated by the numeral 5, which is equipped with intake and 75 exhaust manifolds 6 and 7 respectively of the well known Ford type, said manifolds being held in connection with the cylinder parts by the clamping members 8 mounted upon the stud bolts 9. 10 indicates the air circulating fan of the water cooling system with which the engine is equipped, said fan being driven by suitable connections with the engine shaft in the usual manner.

In one adaptation of our invention we 80 provide a supporting bracket which, as herein illustrated, may be stamped from a single plate of metal. This bracket includes an arm 11 disposed in a vertical plane, an intermediate angularly disposed portion 12 extending at right angles to said arm, and a second arm 13 on the end of the intermediate portion 12, disposed in spaced 85 parallel relation to the arm 11 and above the plane of the latter arm. The arm 13 is provided upon its lower edge with lugs or 90 projections which are notched or recessed, as at 14. These notches are adapted to receive the clamp supporting stud bolts 9 so that when the clamping nuts are threaded 95 upon the ends of said bolts, the arm 13 of the bracket will be rigidly clamped against the manifold clamping members 8. When 100 the bracket is disposed in this position, it will be observed from reference to Figure 1 105 that the intermediate portion 12 of the

bracket extends transversely and inwardly over the front portion of the engine, so that the forwardly projecting arm 11 will be disposed in a vertical plane substantially directly above the shaft of the fan 10.

Upon one side of the arm 11 a metal block or casting 15 is securely fixed by means of the bolt 16. In this casting a valve 17 of any suitable type is rotatably

10 mounted and controls communication between the air supply pipe 18 and a conducting pipe 19, the latter pipe being extended longitudinally and connected to the intake manifold 6 of the engine. Preferably, the 15 pipe 18 is extended alongside of the exhaust manifold 7 so that atmospheric air entering the open end of the pipe 18 will be preheated before entering the pipe 19. In this pipe 18 a second manually operable 20 valve 20 is mounted.

The rod 21 of the valve 17 is extended exteriorly of the casting 15, and to this rod one end of an arm 22 is fixed. The other end of this arm is angularly twisted, and 25 to the same a relatively broad metal blade 23 is adjustably connected at one of its ends, said end of the blade being provided with a series of longitudinally spaced openings

24 to receive the bolts 25, whereby said 30 blade may be adjustably secured to the arm 22. The blade 23 is longitudinally curved, as shown in Figure 1, and is positioned adjacent to and at the rear of the fan 10, and in the vertical plane of the axis of

35 the fan shaft, as clearly appears from Fig. 3. As is well known, in engines of the Ford type, the vertical plane of the axis of the fan shaft passes through substantially the center line of the engine casing and cylinders. Accordingly, in the described 40 construction, the plate 23 is interposed between the fan 10 and the engine casing, so that it is out of the path of air currents resulting from movement of the car, and 45 is consequently affected to a minimum degree by such air currents. The action of the plate 23 therefore depends upon the speed of the fan and hence of the engine, regardless of the speed of travel of the 50 car.

To the casting 15 an arm 26 is fixed. One end of a coil spring 27 is attached to this arm, and the other end of said spring is adapted for adjustable connection to the 55 arm 22, said arm having a series of longitudinally spaced openings 28 therein, through any one of which the end of the spring may be engaged. It will be understood that by a proper adjustment of the 60 connection of said spring with the arm 21 the tension of the spring may be suitably regulated.

In the operation of the device as above described, when the engine is started both 65 of the valves 17 and 20 are closed so that

cold air will not be drawn into the engine cylinders. After the engine has been started, and its speed increases, the manually operable valve 20 is opened, and as the speed of rotation of the fan 10 increases correspondingly to the engine speed, it will be understood that the current of air driven rearwardly by this fan against the forward concave face of the blade 23 forces said blade rearwardly, thereby rotating the valve 17 and against the tension of the spring 27. This valve 16 is thereby opened from its normal closed position, the extent of such opening depending upon the force exerted against the blade 23. Thereby communication is established between the pipes 18 and 19, and by reason of the vacuum in the engine cylinders, heated atmospheric air will be drawn through the pipes 18 and 19, and enter into the intake manifold, where it becomes thoroughly mixed with the combustible mixture, supplied by the carburetor, prior to the entrance of such mixture into the engine cylinders. Thus a leaner mixture will be supplied to the cylinders, resulting in a maximum development of power with a minimum consumption of fuel.

From the foregoing description considered in connection with the accompanying drawings, the construction, manner of operation and several advantages of our invention will be clearly understood. It will be appreciated that such a device will be highly sensitive in its action, and will operate automatically to control the volume of auxiliary atmospheric air admitted to the intake manifold in proportion to variations in speed in the operation of the engine. By properly adjusting the blade 23 upon the arm 22, said blade may be so positioned relative to the fan 10 that it will receive the full force or impact of the rearwardly directed air from said fan, said force causing a rotary movement of the valve 17.

In view of the relatively small number of parts constituting the device, and their simple form and construction, it will be apparent that there is little to get out of order, so that the present invention provides a very desirable accessory for motor vehicle engines.

We have above referred to a particular construction of supporting bracket for the auxiliary air supply valve and its adjunctive parts, which is particularly designed for the application of our present improvement to the Ford type of automobile engine. It is, however, manifest that by adopting other forms of this supporting bracket, and incorporating such other minor mechanical alterations as may be necessary, the device can as well be used in connection with other makes of motor vehicle engines. It is further to be

borne in mind that while we have herein disclosed one satisfactory and practical embodiment of the device, the same may, nevertheless, be exemplified in numerous other modified constructions, and we, therefore, reserve the privilege of adopting all such legitimate changes and modifications in the form, construction and relative arrangement of the several elements as may be fairly embodied 10 within the spirit and scope of the invention as claimed.

We claim:

1. In combination with a manifold, an air supply thereto, a valve governing the air supply, and a vane positively coupled to operate said valve in either direction and lying rearwardly of the motor fan and in line with the draft therefrom, said vane being biased in the closed position of the valve 15 to a forwardly projecting position with the plane of the vane forming a small acute angle with the horizontal whereby to receive diagonally a portion only of the draft from the fan, the pitch or initial inclination 20 of the vane being such as to be affected only lightly at first, the draft gradually raising the vane progressively nearer to a vertical position during increased speeds of the engine proportionally to such increased speeds 25 and in direct proportion to the force of the draft upon the vane, said vane adapted to move to a substantially vertical position whereupon the valve is arranged to be in a fully open position, said vane in the vertical 30 position adapted to lie at substantially right angles to the direction of the air currents set up by said motor fan whereby to secure the full effective force of the air currents 35 to hold the valve in the fully open position.
2. In an auxiliary air supply device for internal combustion engines, an air supply pipe adapted to be connected to the intake side of the engine, a valve in said pipe controlling the flow of air therethrough, means

for normally urging said valve into a closed position, a pivoted member connected to said valve and arranged in the line of draft of the cooling fan of the engine for receiving impact of air from said fan for successively opening the valve by increased speed of the engine, said pivoted member being inclined forwardly toward the fan for normally presenting an inclined working face to the line of draft and adapted when operated to successively present said working face toward a right angular position with respect to the line of the draft whereby to increase resistance to the line of draft and effect increased pressure on said pivoted member, and means for adjusting the working length of said pivoted member whereby to vary the effective leverage of said member relatively to the said means for normally urging the valve into a closed position.

3. In an auxiliary air supply device for internal combustion engines, a pipe connected at one end to the intake manifold of an internal combustion engine, a bracket mounted upon the forward end of the engine for supporting said pipe with one end opening above the engine to receive heated air in the pipe, a normally closed valve mounted in said pipe, air pressure operated means connected to said valve and arranged in line with the cooling fan of the engine for opening said valve upon operation of the engine at a predetermined rate of speed, and a manually controlled valve mounted in said pipe adapted for operation independently of the first mentioned valve whereby to offset admission of air to said intake manifold independently of the operation of said first valve.

In testimony that we claim the foregoing as our invention, we have signed our names hereunder.

CHARLES A. RIVERS.
FRANCIS BACON STUART.
